UNITED STATES PATENT OFFICE

HARRY R. COLE, OF WILMINGTON, DELAWARE, ASSIGNOR TO TILE AND MANTEL CONTRACTORS ASSOCIATION OF AMERICA, OF WILMINGTON, DELAWARE, A CORPORATION OF DELAWARE

DESIGN FOR A SIGN

Application filed October 5, 1929. Serial No. 32,958. Term of patent 14 years.

To all whom it may concern:

Be it known that I, HARRY R. COLE, a citizen of the United States, residing at Wilmington, county of New Castle, State of Delaware, have invented a new, original, and ornamental Design for Signs, of which the following is a specification, reference being had to the accompanying drawings, forming a part thereof.

In the drawing:

Fig. 1 is a front elevation of the new design; and Fig. 2 is an end view.

I claim:

The ornamental design for a sign, as shown.

HARRY R. COLE.
